Philip Spofford's Metamora
Letters Patent

The Schedule referred to in the Letters Patent and making part of the same containing a description in the words of the late Philip Spofford himself of his improvements in the musical instrument called Metamora.

The plettaphia is a portable or may be made a stationary musical instrument, it is made of wood & may be made of other materials, it is flat and may be curved. It is shaped according to the convenience & may be made of different shapes, to be played with a bow on strings inserted in the tension thereof sustained by the sounding board. & passing over a bridge the assistance of which from the nut is short in comparison with the body of the instrument. It may be constructed of any large size, & yet its soundeth the very full, & of the highest pitch, or may be of a lower one. (3) When larger strings than those of violin are applied to it, & more length is given to them from the bridge to the nut, in the known proportion, its pitch may be brought to that of the alto. By the application of larger & longer strings, & giving to them a greater length from the bridge to the nut, its pitch may be brought to that of the bass & double bass, with bodies unconsciously larger & of different forms from those of the said instruments (3) The body of the plettaphia is of wood & may be made of metal & other materials. Its form may be varied according to fancy. Its handle may be made broad or narrow, large or small. Its varnish may be of oil or other varnishes. It is tuned by fifths, & may be tuned by fourths or other intervals. It has strings of catgut, as the violin & alto, to be played with the violin bow, or the one adapted to it. & in addition may have wire strings of different size & length, inserted in the sounding board with fingers or other contrivances, & they may be tensioned up to a tail piece, or to similar things. The sound by which

They are dividing one of many examples of different instruments
and one example is fancy form. The finger board is of wood
and made of different materials & form. The bridge is of wood
and made of different materials. The hoop or support of the
instrument are wider than in another. It may be made wider
or narrower in different parts all alike (4) The holes of the
plectra box are in the shape of an S and may be circular or of
any other figure. The instrument has two holes & may have
one or but one smaller or larger. They are placed at the sides
& may be placed in the middle of the sounding board or in an
other part of the instrument. It has one sounding board only
thinner (5) The plectra box may be placed on a suitable box
of different construction taught here. It may be placed on a
permanent box so as to be played in standing & may by the former
mounted on steps or foot stool. It may have a cap fastened
just above each hole to give the interval of the strings from
fingers to finger (6) The names which distinguish the different
kinds of the instrument are the following. Plectra box violin or
small size. Also also 3 way. Ditta violin plectra 3 way called
chamise box. Plectra box with four holes 3 way & 4 way called
Ditta box 3 way & 4 way (7) The applying of the
strings to a large sounding board by running them at the
sounding board & giving to them a smaller relative distance
from the bridge to the neck (as in the plectra box) which makes
a large stringed instrument produce the high pitch of the cord
in a much fuller sound & of the kind required to perform the
principal part in music & which gives to the box plectra a
fuller sound & so letting also the music of execution in close
with your practice as has invention. The only feature here
left to be the true & original inventor of the above instrument
as herein specified (8) Concerning the use of the plectra box, it
is to be observed that the way of holding the instrument being
calculated for females to perform on it they are afraid of it as

are accompanied to the voice. The manner of holding the guitar like this is calculated for females as well as males. When held vertically for males it is placed at the side, the lower part of the guitar like resting on the floor. Small platter like are placed by arm between the knee. (9) The evolution of your platter one which is known to the invention of the platter like was to enable performances of music to accompany & support their voices in a choir upon a stringed instrument capable of producing long sounds with their modifications of voice & likewise to enable male performers to leave a choir with a stringed instrument easy to tune as well calculated as the violin for leaving & where business of playing is more congenial than that of the violin with the vicinity of the place of performance.
